UNITED STATES PATENT OFFICE.

JOSEPH T. FENTON, OF PHILADELPHIA, PENNSYLVANIA.

VALVE-GEAR.

SPECIFICATION forming part of Letters Patent No. 729,313, dated May 26, 1903.

Application filed February 11, 1903. Serial No. 142,823. (No model.)

To all whom it may concern:

Be it known that I, JOSEPH T. FENTON, a citizen of the United States, and a resident of Philadelphia, in the county of Philadelphia and State of Pennsylvania, have invented 5 a new and Improved Valve-Gear, of which the following is a full, clear, and exact description.

The invention relates to multiple-cylinder engines; and its object is to provide a new and improved valve-gear which is simple and durable in construction, easily manipulated, and arranged to enable the operator to quickly reverse the engine, to cut off the admission 15 of the motive agent to a nicety, to control the admission of the motive agent to and from the cylinders in proper succession and according to the speed desired and the load carried.

20 The invention consists of novel features and parts and combinations of the same, as will be more fully described hereinafter and then pointed out in the claims.

A practical embodiment of the invention 25 is represented in the accompanying drawings, forming a part of this specification, in which similar characters of reference indicate corresponding parts in all the views.

Figure 1 is a side elevation of the improvement as applied to a three-cylinder engine. Fig. 2 is a sectional side elevation of the same on the line 2 2 of Fig. 3. Fig. 3 is a cross-section of the same on the line 3 3 of Fig. 1. Fig. 4 is a rear face view of the admission 30 and exhaust valve. Fig. 5 is a sectional side elevation of the improvement on the line 5 5 of Fig. 3. Fig. 6 is a similar view of the same on the line 6 6 of Fig. 3. Fig. 7 is a like view of the same on the line 7 7 of Fig. 3. Fig. 8 35 is a similar view of the improvement shown in Fig. 6, the parts being in a different position; and Fig. 9 is a face view of a bearing for the main shaft.

The engine-cylinders A, A', and A² are symmetrically disposed on a closed casing B, into which open the inner ends of the said cylinders, and in the latter are mounted to reciprocate pistons C, C', and C², connected by pitmen D, D', and D² with the crank-arm E' 40 of the main shaft E, journaled in suitable

bearings on the casing B and in the outer end of a steam-chest F, bolted or otherwise secured to the face B' of the casing B.

The steam-chest F is provided with a steam-inlet pipe G, connected with a boiler or other suitable source of motive-agent supply, and an exhaust-pipe H leads from the casing B, preferably at the bottom thereof, as plainly indicated in the drawings.

Cylinder-ports a, a', and a² extend from the outer ends of the cylinders and lead to the face B' of the casing, and the inlet ends of the said ports at the face B' are arranged in a circle to register with elongated ports b, b', and b², formed in a circular reversing and 65 shut-off valve I, concentric with the shaft E, as plainly illustrated in the drawings.

The valve I is mounted to turn on the hub J' of a cut-off valve J, having pairs of ports c, c', and c², adapted to register with the 70 ports b, b', and b² in the reversing and shut-off valve I. The pairs of ports c, c', and c² are adapted to register with an admission-port d, formed in an admission and exhaust valve K, mounted to turn loosely on the shaft 75 E, and the rear face of this admission and exhaust valve K is provided with an exhaust-cavity e, opening to a central aperture J² in the valve J, which aperture registers with a central aperture I', formed in the valve I, 80 and this aperture registers with an opening B², leading to the inside of the casing B, as plainly shown in Fig. 3.

On the outer face of the admission and exhaust valve K are arranged spaced pins K' 85 and K², (see Figs. 3 and 5,) adapted to be engaged by a pin K³, extending from a hub K⁴, secured to the main shaft E, so that when the latter rotates the pin K³ engages either of the pins K' or K² to turn the valve K in the direction in which the engine is to run. The valves I and J are under the control of the operator and are adapted to turn independently one of the other, and for this purpose the peripheral face of the valve I is provided 95 with gear-teeth I² (see Fig. 7) in mesh with a segmental gear-wheel L, attached to the inner end of a shaft L', provided at its outer end with a handle L² within reach of the operator. The other valve J is provided on its 100

peripheral face with gear-teeth J^3 in mesh with a segmental gear-wheel N , fastened on the inner end of a hollow shaft N' , journaled in suitable bearings on the steam-chest F , and on the outer end of this shaft N' is secured a handle N^2 , likewise within reach of the operator. As shown in Fig. 3, the shaft L' has its bearings in the hollow shaft N' .

Now by the arrangement described the operator in swinging the handle L^2 to a vertical position causes its shaft L' and segmental gear-wheel L to turn the valve I into a shut-off position—that is, to move the ports b , b' , and b^2 out of register with the cylinder-ports a , a' , and a^2 . When the handle L^2 is moved to the right into the position shown in Figs. 1, 3, and 7, then the ports b , b' , and b^2 register with the ports a , a' , and a^2 , and when the handle L^2 is thrown over into a left-hand-side position then the valve I is turned so as to bring the ports b , b' , and b^2 in register with the ports a , a' , and a^2 to reverse the engine. The valve J is turned in a similar manner on swinging the handle N^2 from a vertical position to the right or to the left; but in this case the position of the handle N^2 determines the relation of the pairs of ports c , c' , and c^2 to the corresponding ports b , b' , and b^2 —that is, only one of the ports of each pair may be moved in register with the corresponding port in the valve I to reduce the admission of steam to the said ports and to the cylinder-ports to a nicety—and hence the operator is enabled to give more or less steam by manipulating the handle N^2 correspondingly, according to the speed desired and to the load connected with the main shaft E . It is understood that when the valve I is shifted to reverse then the admission and exhaust valve K remains stationary for a short time—that is, until the pin K^3 has traveled from the pin K^2 over onto the pin K' to now carry the pin along and with it the valve in the reverse direction of the arrow f' .

45 The valves I and K are approximately the same in general construction as the corresponding valves shown and described in the application for Letters Patent No. 102,195, filed by me April 10, 1902, and hence further 50 description of the same is not deemed necessary, it being, however, understood that the cut-off valve J is interposed between the valves I and K and has a pair of ports for each port in the valve I to regulate the admission and exhaust of the steam to a nicety.

55 A bearing O is preferably located in the opening B^2 of the casing to give the main shaft E as much support as possible to insure an easy running of the engine.

60 Having thus described my invention, I claim as new and desire to secure by Letters Patent—

65 1. A valve-gear for multiple engines, comprising a revoluble admission and exhaust valve, rotating with the engine-shaft, a reversing and shut-off valve, adapted to be

turned and controlling the motive agent to and from the cylinder-ports, and a cut-off valve, adapted to be turned independent of the said reversing and shut-off valve, and interposed between the said admission and exhaust valve and the reversing and shut-off valve, as set forth. 70

2. A valve-gear for multiple engines, comprising a revoluble admission and exhaust valve, rotating with the engine-shaft, a reversing and shut-off valve, adapted to be turned and controlling the motive agent to and from the cylinder-ports, and a cut-off valve, adapted to be turned independent of the said reversing and shut-off valve, and interposed between the said admission and exhaust valve and the reversing and shut-off valve, the said cut-off valve having pairs of ports, each pair for register with a port in the 80 said reversing and shut-off valve, as set forth. 85

3. A valve-gear for multiple engines, comprising a revoluble admission and exhaust valve, rotating with the engine-shaft, a reversing and shut-off valve, adapted to be turned and having elongated ports, each for register with a corresponding cylinder-port, to control the admission and exhaust of the motive agent to and from the cylinders, and a cut-off valve, adapted to be turned independent of the said reversing and shut-off valve, and interposed between the said admission and exhaust valve and the said reversing and shut-off valve, the said cut-off valve having pairs of ports, one pair for each 100 of the elongated ports in the said reversing and shut-off valve, as set forth.

4. A valve-gear for multiple engines, comprising a revoluble admission and exhaust valve, rotating with the engine-shaft, a reversing and shut-off valve, adapted to be turned and having elongated ports, each for register with a corresponding cylinder-port, to control the admission and exhaust of the motive agent to and from the cylinders, and a cut-off valve, adapted to be turned independent of the said reversing and shut-off valve, and interposed between the said admission and exhaust valve and the said reversing and shut-off valve, the said cut-off 110 valve having pairs of ports, one pair for each of the elongated ports in the said reversing and shut-off valve, the said pairs of ports being also adapted to register alternately with the admission-port and the exhaust-cavity in 115 the said admission and exhaust valve, as set forth. 120

5. A valve-gear for multiple engines, comprising a revoluble admission and exhaust valve, rotating with the engine-shaft, a reversing and shut-off valve, adapted to be turned and controlling the motive agent to and from the cylinder-ports, a cut-off valve, adapted to be turned independent of the said reversing and shut-off valve, and interposed 125 between the said admission and exhaust valve and the reversing and shut-off valve, a han- 130

dled shaft carrying a segmental gear-wheel in mesh with teeth on the said reversing and shut-off valve, and a second handled shaft, carrying a segmental gear-wheel, in mesh with the said cut-off valve, to allow the operator to turn the said reversing and shut-off valve and the said cut-off valve independently one of the other, as set forth.

In testimony whereof I have signed my name to this specification in the presence of 10 two subscribing witnesses.

JOSEPH T. FENTON.
